US00D896847S

(12) **United States Design Patent** (10) **Patent No.:** **US D896,847 S**
(45) **Date of Patent:** **** Sep. 22, 2020**

(54) **PUMP**

(71) Applicant: **Insera Therapeutics, Inc.**, Sacramento, CA (US)

(72) Inventors: **Vallabh Janardhan**, Dallas, TX (US); **Vikram Janardhan**, Sacramento, CA (US)

(73) Assignee: **Insera Therapeutics, Inc.**, Sacramento, CA (US)

(**) Term: **15 Years**

(21) Appl. No.: **29/684,193**

(22) Filed: **Mar. 19, 2019**

Related U.S. Application Data

(60) Continuation of application No. 29/634,405, filed on Jan. 22, 2018, now Pat. No. Des. 847,864, and a continuation of application No. 29/678,622, filed on Jan. 30, 2019, now Pat. No. Des. 850,490, which is a division of application No. 29/634,405, filed on Jan. 22, 2018, now Pat. No. Des. 847,864, application No. 29/684,193, which is a continuation of application No. 29/678,632, filed on Jan. 30, 2019, now Pat. No. Des. 847,866, which is a division of application No. 29/634,405, filed on Jan. 22, 2018, application No. 29/684,193, which is a continuation of application

(57) **CLAIM**

The ornamental design for a pump, as shown and described.

DESCRIPTION

FIG. 1 is a front, left, and top perspective view of a pump; FIG. 2 is a back, right, and bottom perspective view of the pump of FIG. 1;

FIG. 3 is a front elevational view of the pump of FIG. 1;

FIG. 4 is a back elevational view of the pump of FIG. 1;

FIG. 5 is a top plan view of the pump of FIG. 1;

FIG. 6 is a bottom plan view of the pump of FIG. 1;

FIG. 7 is a right elevational view of the pump of FIG. 1; and,

FIG. 8 is a left elevational view of the pump of FIG. 1.

The broken line portions show unclaimed subject matter only and form no part of the claimed design.

1 Claim, 7 Drawing Sheets

 U.S. Appl. No. 13/953,540 (now U.S. Pat. No. 8,715,314), filed Jul. 29, 2013 (dated May 6, 2014), Vascular Treatment Measurement Methods.
 U.S. Appl. No. 14/012,866 (now U.S. Pat. No. 8,845,678), filed Aug. 28, 2013 (dated Sep. 30, 2014), Two-Way Shape Memory Vascular Treatment Methods.
 U.S. Appl. No. 14/012,862 (now U.S. Pat. No. 8,733,618), filed Aug. 28, 2013 (dated May 27, 2014), Methods of Coupling Parts of Vascular Treatment Systems.
 U.S. Appl. No. 14/012,904 (now U.S. Pat. No. 8,789,452), filed Aug. 28, 2013 (dated Jul. 29, 2014), Methods of Manufacturing Woven Vascular Treatment Devices.
 U.S. Appl. No. 14/012,913 (now U.S. Pat. No. 9,179,995), filed Aug. 28, 2013 (dated Nov. 10, 2015), Methods of Manufacturing Slotted Vascular Treatment Devices.
 U.S. Appl. No. 14/012,903 (now U.S. Pat. No. 8,870,901), filed Aug. 28, 2013 (dated Oct. 28, 2014), Two-Way Shape Memory Vascular Treatment Systems.
 U.S. Appl. No. 14/013,411 (now U.S. Pat. No. 8,728,116), filed Aug. 29, 2013 (dated May 20, 2014), Slotted Catheters.
 U.S. Appl. No. 14/013,376 (now U.S. Pat. No. 8,735,777), filed Aug. 29, 2013 (dated May 27, 2014), Heat Treatment Systems.
 U.S. Appl. No. 14/013,421, filed Aug. 29, 2013, Laser Cutting Systems.
 U.S. Appl. No. 14/013,448, filed Aug. 29, 2013, Woven Vascular Device End Treatments.
 U.S. Appl. No. 14/013,588 (now U.S. Pat. No. 8,852,227), filed Aug. 29, 2013 (dated Oct. 7, 2014), Woven Radiopaque Patterns.
